UNITED STATES PATENT OFFICE.

JAMES W. BUCKHART, OF SAN JOSE, CALIFORNIA.

CUTTER-HEAD.

1,122,471.

Specification of Letters Patent.

Patented Dec. 29, 1914.

Application filed December 8, 1913. Serial No. 805,396.

To all whom it may concern:

Be it known that I, JAMES W. BUCKHART, a citizen of the United States, residing at San Jose, in the county of Santa Clara and 5 State of California, have invented certain new and useful Improvements in Cutter-Heads, of which the following is a specification, reference being had to the accompanying drawings.

10 This invention relates to new and useful improvements in cutter and matcher heads and more particularly to an improvement on my former Patent Number 1,062,634, issued May 27th, 1913, and the primary 15 object of the invention is to provide a cutter head having improved bits or cutters in connection therewith.

A further object of the invention resides in providing such cutters or bits as may be 20 arranged in combination, one with the other, whereby to provide improved patterns or designs in wood.

In addition to the numerous other objects 25 set forth in my prior patent, a still further object resides in providing a device which is simple and durable in construction, inexpensive to manufacture and one which will be very efficient and useful in operation.

30 With these and other objects in view, the invention consists in the novel features of construction, combination and arrangement of parts as will be hereinafter referred to and more particularly pointed out in the 35 specification and claims.

In the accompanying drawings forming a part of this application, Figure 1 is a side elevation of a cutter head constructed in accordance with my invention, with parts broken away. Fig. 2 is a bottom plan view thereof. Fig. 3 is a section as seen on line 3—3, Fig. 1. Fig. 4 is a plan view of one of the sliding members. Fig. 5 is a plan view of one of the bits used in the preferred 45 form of the device. Fig. 6 is a similar view of an additional form of cutter used in the preferred form of the device.

In describing my invention, I shall refer to the drawings in which similar reference 50 characters designate corresponding parts throughout the several views and in which 1 indicates a sleeve or hub which is enlarged

at one end thereof to form a head 2, the latter being dodecagonal in cross section. This head 2 which is slotted, forms a dodecahedron and the alternate faces thereof have formed or otherwise secured thereon the right angular projections 3, the same extending from one end of the head for the greater portion of the length thereof. The 55 faces of these projections 3 are arranged angular with respect to the faces of the head on which the same are formed and the flat plate-like cutters 4 are mounted on one face of said projections. Angular plates or cap 60 members are adapted for application to the faces of the projections and the cutters to secure the latter in place and set screws 6 are carried by the plates or cap members for reception in threaded openings in the 65 faces of the projections, against which the cutters are directly received. The inner edges of the cutters 4 are slotted, as shown at 7 to receive therethrough the shanks of the set screws 6 and, it will be seen that these 70 cap members will securely retain the cutters in place and admit of adjustability of said cutters on the head member. These 75 cutters 4 may be said to be surface cutters.

The faces of the head 2 alternating the 80 faces carrying the projections thereon are provided with slots or channels 8 which extend for the full length of said head and these slots or channels are substantially T-shaped in cross section. Mounted for sliding movement in the T-shaped channels or 85 slots 8 are the strips 9 which are also T-shaped in cross section, and secured in any desired manner to one end of each of said strips 9, is a foot-piece or supporting block 90 10, the blocks 10 being located in the enlarged portion of the slots 8. A projection is also formed on the outer edge of each of the foot-pieces 10 which is designed to contact snugly with a beveled edge 11 formed 95 on the outer edge of one of the faces of each angular projection 3.

Loosely disposed through an opening in each of the foot-pieces or supporting blocks 10, is a bolt 12 having a nut 13 engaged with the threaded outer end thereof and this bolt and nut are adapted to clamp a pair of cutters or bits 14 and 15 against one another and against one face of the foot-piece or

supporting block 10. These bits or cutters 14 and 15 are designed to also fit snugly between the walls of the adjacent projections and have their cutting edges projecting outwardly beyond the edges of the latter. The bits or cutters 14 are milled, while the bits 15 have straight edges, the straight cutting edges being provided on a tooth-like projection thereof. The milled cutters or bits 14 are adapted to face against the foot-pieces or cutting blocks 10 while the bits or cutters 15 receive the heads of the bolts 12 thereagainst and said latter cutters or bits have the faces thereof offset, as shown at 16, to receive the heads of said bolts therein. The bits or cutters 14 and 15 are also slotted, as shown at 17 to receive the shanks of the bolts therethrough and from this construction, it will be seen that said bits or cutters 20 are capable of adjustment radially.

The sliding strips 9 are axially adjustable in the slots 8 in the head, the strips 9 being provided with threaded openings in which set screws are mounted, the screws carrying washers 19 which are disposed between the heads of the bolts 18 and the periphery of the head 2 on opposite sides of the slots 8. When the heads of the bolts 18 are turned to engage the washers 19, the strips 9 are drawn outwardly so as to bind the outer faces of the heads of the strips against the walls of the slots as shown in Fig. 2 of the drawings, to hold the strips in their adjusted positions. The sliding strips 9 with the foot-pieces thereon may be said to be cutter carriers and when it is desired to provide a pattern of particular design, a pair of such cutter carriers may be provided in each channel or slot, the same being disposed therein from opposite ends of the same. In the drawings, I have shown such a construction, wherein a pair of such cutter carriers are provided, each carrying a pair of cutters indicated as 14 and 15, and disposed in the channels from opposite ends thereof, so as to permit the cutters 15 to be opposed to one another. It will, of course, be understood that a single cutter carrier with cutters thereon, or a pair of the same may be provided in connection with each channel or slot, as is found desirable.

From the foregoing it will be seen that I have provided a simple, inexpensive and efficient means for carrying out the objects of the invention and while I have particularly described the elements best adapted to perform the functions set forth, it is obvious that various changes in form, proportion and in the minor details of construction 55 may be resorted to without departing from

the spirit or sacrificing any of the principles of the invention.

Having thus described this invention, what I claim is:—

1. In a cutter head, a hub enlarged at one end and designed to form a prismatic head, projections formed on the head and spaced at regular intervals throughout the periphery thereof, cutters adjustably carried on said projections, said head being provided with longitudinal slots in the spaces between said projections, strips adjustably mounted in the slots of said head and each being provided with a foot piece, said foot pieces being designed to fit snugly between the adjacent projections, a bolt mounted in each of the foot pieces, additional cutters carried on each of said bolts and also fitting snugly between the adjacent projections of the head, one of said additional cutters on each bolt having a recess formed in the outer face thereof to receive the head of the bolt whereby the bolt head is disposed flush with the outer face of the cutter, and means for adjustably securing 85 said strips in the slots.

2. In a cutter head of the class described, a hub enlarged at one end and designed to form a prismatic head, projections formed on the head and spaced at regular intervals throughout the periphery thereof, cutters adjustably carried on said projections, said head being formed with longitudinal slots in the spaces between said projections, a pair of strips adjustably mounted in each of the slots and provided at their opposing ends with a foot piece, said foot pieces being designed to fit snugly between the adjacent projections, additional cutters carried on each of said foot pieces, the opposing cutters of each pair of foot pieces being formed with a recess in its opposing face, bolts disposed through said cutters and said foot pieces, the heads of said bolts being adapted for engagement in the recesses in said opposing cutters, whereby the opposing faces of the cutters which are mounted on each pair of foot pieces are adapted to engage flush against each other, means mounted on said bolts to secure said cutters in position 105 upon said foot pieces, and means for securing said strips in adjusted position in the slots.

In testimony whereof I hereunto affix my signature in the presence of two witnesses.

JAMES W. BUCKHART.
